UNITED STATES PATENT OFFICE.

MEREDITH LEITCH, OF POUGHKEEPSIE, NEW YORK, ASSIGNOR TO THE DE LAVAL SEPARATOR COMPANY, OF NEW YORK, N. Y., A CORPORATION OF NEW JERSEY.

CENTRIFUGAL OIL PURIFIER.

1,415,881.

Specification of Letters Patent. Patented May 16, 1922.

Application filed April 22, 1920. Serial No. 375,735.

To all whom it may concern:

Be it known that I, MEREDITH LEITCH, a citizen of the United States, residing at Poughkeepsie, county of Dutchess, and State 5 of New York, have invented a new and useful Improvement in Centrifugal Oil Purifiers, of which the following is a full, clear, and exact description, reference being had to the accompanying drawings, which 10 form a part of this specification.

My invention is an improvement in centrifugal separators designed for separating liquids carrying in suspension some solids.

The object of my invention is to provide 15 a separator from which as large as possible a part of the solids will be removed with the heavier liquid and from which the solids retained in the bowl may be removed with a minimum amount of trouble.

20 In the accompanying drawings, which show a preferred embodiment of my invention:

Fig. 1 shows a section of the frame and a 25 part elevation and part section of the bowl of the machine.

Fig. 2 shows, to a larger scale, a portion of an upper part of Fig. 1.

Fig. 3 is a detail sectional view of the lower portion of the shell *m*.

30 *a* is a masonry foundation, *b* the lower part of the frame and *c* the upper part of the frame. The two parts of the frame are spaced apart by means of a ring 40 which is interposed between flanges 41 on the respective frame sections, bolts 42 extending 35 through the flanges and the ring. At *d* a sphere-like socket is attached to the frame and in it fits a part *e* of a tubular bearing carrying member *f* having a flange *g* supported by cushions *h* on bolts *i*.

Enclosed by the lower part of the tubular member *f*, is a step bearing 50 and a lower guide bearing 51 for a bowl shaft *j*. The bowl shaft carries at its lower end the rotor 45

52 of a motor, the outer casing of which is shown at *k*. The rotor shown is a Pelton wheel, while the stator of the motor is shown as a jet nozzle 53 secured to the lower end of the bearing member *f*. The bowl shaft *j* 50 is guided near its upper end by a bearing *j* carried in the upper end of the tubular member *f* and carries on its upper end the

inner bowl member whose bottom is lettered *n*.

Above the bowl bottom *n* is a set of 55 frustro-conical plates *o*, technically called discs. Above these a special top disc extends inward and upward, as shown at *p*, and has on its upper side several wings or ribs *q*. A disc cage *r*, turned inward above 60 the discs as at *s* and upward at *t*, is forced downward on the ribs *q* and is secured to the bowl bottom *n*, clamping the entire set of discs together. Technically the complete 65 set of discs is called the bowl liner. The part of the disc cage surrounding the outer edges of the discs is perforated.

The lower part of the outer bowl member, or bowl shell *m*, is turned slopingly inward at *y* to form a heavy liquid outlet *w* above 70 the discharge weir ring *w'*. On the upper side of this sloping portion there are wings *x* with lugs *y* which closely fit a ring *z* around the lower edge of the bowl bottom *n*. The upper part of the shell turns inward at 75 11 above the sloping part *s* of the disc cage and upward at 12 concentric with the upward turned neck *t* on the disc cage. The inside of the neck 12 of the bowl shell is threaded to fit an annular nut 13 having an 80 inwardly turned flange 14 resting on a shoulder on the disc cage neck *t*. By this nut the top of the bowl shell *m* is guided and the entire shell raised until the lugs *y* seat in their place in the ring *z*. 85

Secured to, but turnable independently of the nut 13, is a ring 15 having lugs 16 and 17 fitting vertical grooves 18 and 19 in the bowl neck and the neck of the disc cage. Coaction of these lugs and grooves insures 90 that the parts will always be assembled in the same relative positions.

On top of the nut is a ring 20 with an inwardly turned flange 21. Through the nut 13 and the ring 15 there are holes 22 95 annularly extensive.

Supported on top of the frame is a central feed cup 23 with the annular regulating tube 24 for the material to be separated and an annular feed cup 25 with the second annular regulating tube 26 for a cushioning or carrier liquid. 100

Through the bowl bottom *n*, approximately in line with the inner edges of the

disc, is a set of holes 33, forming the outlet for the lighter liquid.

Through the top disc and through all of the discs *o*, near their outer peripheries, are 5 holes 27.

Around the lower edge of the bowl is a depending ring 28. The frame of the machine is made to fit as closely around the bowl as proper clearances will permit and 10 is provided with a channel 29 to receive the ring 28. Near the top of the frame is a pipe connection 30.

The bowl shell *m* comprises an upper section and a lower section, as shown. The two 15 sections of the bowl shell are held together by a sectional ring 310 of channel cross section. The ring 310 is held to the bowl by an outer ring 31 bolted to the inner ring, as shown. On the upper flange 41 of the lower 20 part *b* of the frame, within the ring 40 of the frame, and below the ring 31 of the bowl shell, are several lugs 32.

In operation, the materials to be separated are fed into the cup 23 and pass downward through the regulating tube 24 into the space above the top disk *p*. The wings *q* cause these materials to rotate at the same speed as the bowl. If there are very heavy 25 solids they may be thrown out of the liquid 30 at once, pass through the perforations in the disc cage and collect against the inside of the bowl shell *m*. The liquids and some 35 of the lighter solids will pass down through the holes 27 and distribute between the discs *o*, where centrifugal force will cause the heavier liquid and the solids to move toward the outside, pass through the perforations in the disc cage, around the edge of the ring *z* and finally out of the outlet *w*. The 40 lighter liquid will move toward the center of the bowl and pass down through the holes 33.

If the liquids, being separated, contain 45 much solid matter that tends to collect against the inside of the shell, a cushioning or carrier liquid may be supplied to the annular feed cup 25. This will flow down through the regulating tube 26 and the holes 50 22 into the space between the sloping top *s* of the disc cage and the sloping top 11 of the bowl shell. Because this space is made as smooth as possible, the inertia of the liquid is able to cause it to lag as it passes outward and at the outside rotate much slower than 55 the bowl. This causes a scouring action against the inside of the bowl shell and also reduces the centrifugal force acting on solid particles as they approach the shell. These 60 two actions together result in the carrying out with the liquid of a much greater proportion of the solids than occurs without the cushioning or carrier liquid. This action may be increased by using, as a cushion or carrier, concentrated brine or some other 65 liquid of high specific gravity.

When, in spite of all efforts to prevent it, the bowl shell becomes loaded with solids, the power is shut off and water is passed through the inlet 30 to the space between the bowl and the casing and, by liquid friction, soon brings the machine to a standstill. The ring 28 running in the channel 29 acts to prevent too free an escape of water from the braking space. 70

After the bowl stops the covers 23 and 75 25 may be removed and a wrench provided for the purpose attached to the nut 13. By unscrewing this nut the bowl shell is allowed to drop until the ring 31 rests on the lugs 32. The nut 13 and ring 15 may then be removed, leaving the bowl shell safely clear 80 of the bowl bottom *n* and of the disc cage *r-s*, so that they may be rotated independently.

A strong jet of water may be shot down 85 inside the neck *p* of the top disc against the inner edges of the discs *o*. With the discs in rotation, centrifugal force will help this water to pass rapidly between the discs, washing out any sediment that may have 90 collected there. The water, escaping at high velocity from the edges of the discs, will impinge, with a scouring action, against the inside of the stationary bowl shell, loosen the dirt deposited there and wash it out 95 through the heavy liquid outlet *w*.

If the machine has been run so long without cleaning that dirt is packed too hard to allow the bowl shell to drop down, it is possible to direct a high pressure water jet 100 through the space from which the nut 13 is removed and soon loosen it. The previously described cleaning process may then be followed.

After the sediment is cleaned out of the 105 bowl, the liner and bowl bottom are turned until the vertical grooves in the disc cage are in line with those in the bowl neck. The ring 15 may then be dropped into place with its lugs 16 and 17 in the grooves 18 and 19 110 and the bowl shell be drawn up to its running position by the nut 13.

I do not herein claim that part of the above described construction providing for the flowing of a liquid between the rotatable 115 bowl shell and the closely surrounding bowl casing and the maintenance of a body of such liquid in frictional contact with both the bowl and casing so as to arrest the rotation of the bowl, as the same forms the subject-matter of a divisional application filed July 8, 1921, Serial No. 483,192. 120

Having now fully described my invention, what I claim and desire to protect by Letters Patent is:—

1. In a centrifugal separator, a compound 125 rotatable bowl comprising an inner member with a perforated periphery and an outer shell member, in combination with means to rotate the inner member either in- 130

- dependently of, or in unison with, the outer member.
2. In a centrifugal separator, a compound rotatable bowl comprising an inner member 5 with a perforated periphery and an outer shell member, in combination with means to rotate the inner member, and means operable to connect the two members so that they will rotate in unison and to disconnect them so that the inner member will rotate independently.
3. In a centrifugal separator, the combination with a rotatable bowl bottom and liner, of a bowl shell, means to secure said shell to said bowl bottom and liner so as to rotate therewith and other means to support said shell stationary and concentric with said bowl bottom and liner so that said bottom and liner may be rotated therein independently thereof.
4. In a centrifugal separator, the combination with a flexibly supported hollow member having a lateral bearing near its upper end and a step bearing and a second 25 lateral bearing near its lower end, and a shaft carried by said bearings, of a bowl bottom and liner carried by said shaft and a bowl shell adapted to be attached to and rotated with said bottom and liner and also 30 adapted to be stationarily supported concentric with and independent of said bottom and liner.
5. In a centrifugal separator, the combination with a bowl bottom and a set of frusto-conical discs superposed thereon, of a disc cage secured to the bowl bottom and surrounding the disc and turned inward above them, the part of said disc cage surrounding the discs being perforated.
- 40 6. In a centrifugal separator, the combination with a bowl bottom and a set of frusto-conical discs superposed thereon, of a disc cage secured to the bowl bottom and surrounding the discs and turned inward above them, the part of said disc cage surrounding the discs being perforated, and an outer bowl shell spaced from the disc cage.
7. In a centrifugal separator, the combination 50 with a bowl bottom and a set of frusto-conical discs superposed thereon, of a disc cage secured to the bowl bottom and surrounding the discs and turned inward above them, the part of said disc cage surrounding the discs being perforated, an outer bowl shell spaced from the disc cage, means to rotate the bowl bottom, discs and disc cage, and means to operatively connect and disconnect said rotatable elements with the outer bowl shell so that said elements may be rotatable in unison with, or independently of, the bowl shell.
8. A centrifugal separating bowl provided 60 with an inlet for separable materials and means to cause such material to rotate at the same speed as the bowl, said bowl having also a second inlet adapted to receive a cushioning liquid for solids and smooth passages wherein said cushioning liquid may rotate more slowly than the bowl.
9. In a centrifugal separator bowl, the combination with a bowl having separate inlets, one for materials to be separated and another for a cushioning liquid, and passages communicating with the respective inlets, of means in the passage communicating with the first inlet tending to compel the materials flowing through said passage to rotate at the speed of the bowl, the other passage being unobstructed to allow the inertia 70 of the cushioning liquid flowing therethrough to cause it to lag behind the rotative speed of the bowl and effect a scouring action against the inside of the bowl shell.
10. In a centrifugal bowl, the combination with a bowl having two outwardly extending inclined passages, one for the materials to be separated and the other for a cushioning liquid, of a wing in the first passage, the other passage being unobstructed.
11. In a centrifugal separator, a compound rotatable bowl comprising a disc cage having a conical portion and an outer shell with a similar conical portion, there being a 80 passage for materials to be separated within the conical portion of the disc cage and a passage for a cushioning liquid between the conical portions of the two bowl members, and separate inlets communicating with the 85 separate passages.
12. In a centrifugal separator, a compound rotatable bowl comprising a disc cage having a conical portion and an outer shell with a similar conical portion, there being a 90 passage for materials to be separated within the conical portion of the disc cage and a passage for a cushioning liquid between the conical portions of the two bowl members, and separate inlets communicating with the 95 separate passages. in combination with a wing in the first passage tending to impart to the materials the speed of the bowl, the 100 second passage being unobstructed.
13. A centrifugal separator comprising an inner member with a perforated periphery and an outer shell, there being an opening through which a high pressure liquid may be directed between the inner member and outer shell to disintegrate and wash out sediment deposited between them.
14. A centrifugal separator comprising a bowl bottom, a separating liner, and means to support and rotate them, and provided with an opening through which a jet of liquid may be projected against the inner 110 face of and into the interstices of the liner to wash sediment therefrom.
15. In a centrifugal separator, the combination with an inner member comprising a bowl bottom and a separating liner, and an 115
- 65 means to cause such material to rotate at 120
- 125
- 130

- 4 outer member comprising a shell, of means to rotate the inner member relatively to the outer member, there being an opening through which a jet of liquid may be projected through the interstices of the liner against the inner wall of the shell, thereby 5 cleaning the liner and scouring the inner wall of the shell.
16. In a centrifugal separator, a compound 10 rotatable bowl comprising an inner member with a perforated periphery and an outer shell member, in combination with means to rotate the inner member, means operable to connect the two members so that they will 15 rotate in unison and to disconnect them so that the inner member will rotate independently, there being an opening through which a jet of liquid may be projected through the inner member against the inner wall of the 20 outer shell.
17. In a centrifugal separating bowl, the combination with a revoluble bowl bottom and liner, of a detachable bowl shell and an opening through which a high pressure 25 liquid jet may be directed between said liner and shell to disintegrate and wash out sediment deposited therein.
18. In a centrifugal separator, a compound 30 rotatable bowl comprising an inner member with a perforated periphery and an outer shell member, in combination with means to rotate the inner member, means operable to connect the two members so that they will 35 rotate in unison and to disconnect them so that the inner member will rotate independently, there being an opening through which a high pressure jet of liquid may be directed between the inner and outer members.
19. In a centrifugal separator, the combination 40 with a rotatable bowl, of an outer frame comprising a lower section and an upper section, opposing circumferential flanges on the respective sections and a ring secured between the flanges.
20. In a centrifugal separator, the combination 45 with a compound bowl comprising an inner rotatable member and an outer member, of means operable to operatively connect and disconnect the outer member and the inner member, a surrounding frame having a recess, and means on the outer bowl member extending into said recess, thereby affording a support for the outer bowl member when it is operatively disconnected from the inner bowl member.
21. In a centrifugal separator, the combination 55 with an inner rotatable bowl member, of an outer bowl member, and an annular nut between the two members engaging one member and threaded on the other.
22. In a centrifugal separator, the combination 60 with an inner rotatable bowl member, of an outer bowl member, a ring between the two bowl members, said bowl member having grooves and lugs on the ring 65 engaging said grooves.
23. In a centrifugal separator, the combination with inner and outer bowl members provided with necks, of a ring between said necks and engaging both bowl members, and an annular nut above the ring and threaded on the neck of one bowl member and engaging the neck of the other bowl member.
24. In a centrifugal separator, the combination 75 with inner and outer bowl members provided with necks, of a ring between said necks and engaging both bowl members, of an annular nut above, and supporting, but turnable relatively to, the ring and threaded on the neck of one bowl member and engaging the neck of the other bowl member.
25. In a centrifugal separator, the combination 80 with an inner rotatable bowl member and an outer bowl member, both members having necks, of a device between, and operatively connecting, the necks of the two members, said connecting device being oriented to allow the admission of a liquid between the two members.
26. In a centrifugal separator, the combination 85 with an outer bowl shell and an inner bowl member having a perforated periphery, of a container for materials to be separated, another container for a cushioning liquid, and means providing conduits from the respective containers to the inner and outer bowl members respectively.
27. In a centrifugal separator, the combination 90 with an inner bowl member and an outer bowl member, of means connecting the two members and operable to move the outer bowl member relatively upward, and coaxing means on the two members to limit the relative upward movement of the outer bowl member.
28. In a centrifugal separator, the combination 95 with an inner bowl member, a surrounding ring, an outer bowl member adjustable upwardly and having an inwardly sloping lower part, and lugs above said sloping lower part adapted, in the upward movement of the outer bowl member, to engage with the ring.
29. In a centrifugal separator, the combination 100 with an inner bowl member having a downward sloping lower part, of an outer bowl member whose lower part slopes downward, and ribs between said downwardly sloping parts.
30. In a centrifugal separator, the combination 105 with an inner bowl member having a downward sloping lower part, of an outer bowl member whose lower part slopes downward, means to adjust the outer bowl member upwardly, ribs on the sloping part of the outer bowl member, lugs at the upper and outer ends of the ribs, and a ring around

the inner bowl member against which said lugs are adapted to fit.

31. A centrifugal machine comprising an inner rotatable member and yieldable driving mechanism therefor, an outer member, means to operate the two members so that they will rotate in unison and to disconnect them so that the inner member will rotate independently, and braking means independ-

ent of said driving mechanism to arrest the rotation of the outer member when it is rotatably connected with the inner member, thereby arresting the rotation of the inner member.

In testimony of which invention, I have 15 hereunto set my hand, at Poughkeepsie, N. Y., on this 17 day of April, 1920.

MEREDITH LEITCH.
